ROBERT H. LAWSON, OF PAWTUCKET, AND AUGUSTIN GAGNÉ, OF CENTRAL FALLS, RHODE ISLAND, ASSIGNEES TO HEMPHILL COMPANY, OF CENTRAL FALLS, RHODE ISLAND, A CORPORATION OF MASSACHUSETTS

NEEDLE BED

Application filed September 16, 1929. Serial No. 392,852.

This invention relates to an improved construction of needle bed and is specifically directed to a construction of needle cylinder adapted to be used in connection with knitting machines of the type disclosed in the patent to Hemphill 933,443, Sept. 7, 1909.

In the accompanying drawings:

Fig. 1 discloses a needle cylinder partly broken away to show a section thereof;

Fig. 1a is a fragmentary view of a modified form of retaining means for the needle walls;

Fig. 2 is a sectional view of a fragment of a needle cylinder with inserted walls, the dimensions and angles being greatly exaggerated;

Fig. 3 is a detail view of a needle wall in vertical elevation;

Fig. 4 is a detail view;

Fig. 5 discloses a modified form of needle wall inserted in slots in the needle cylinder, all parts being shown in section;

Fig. 6 is a sectional view of another modified form of needle wall inserted within cylinder slots, and;

Fig. 7 is a sectional view of still another modified form of needle wall in place in the cylinder slots.

The needle cylinder 1 has its upper portion 2 adjacent the stitch ring 3 cut with slots for the guidance of the needles. A recess is provided therebelow to seat spring bands 4 which latter retain the needles in position as usual in Banner machines. The cylinder at and below the recess is of a diameter less than the upper portion 2 thereof and the cylinder walls below the recess are slotted or grooved to provide parallel slots extending lengthwise of the cylinder. Needle slots 5 are provided by thin metal walls 6 projecting beyond the surface of the cylinder 1. The walls 6 are removably seated in the cylinder slots, and are tapered from the wider edge 7 to the narrower edge 8 thereof which edges are parallel and extend lengthwise of the walls. The tapering shown greatly exaggerated in Fig. 2, is, preferably, uniform from edge 7 to edge 8 of each wall and just sufficient to compensate for the natural divergence of parallel sided walls due to their radial disposition in the cylinder so that the slots 5, between

adjacent walls 6, are of the same width throughout. The cylinder slots as shown in Fig. 2 are correspondingly tapered to fit the needle walls 6 although, if desired, the walls of the cylinder slots may be parallel sided and the needle walls 6 forced or driven therein, the metal of the cylinder walls running sufficiently to provide lateral support for the needle walls 6 and prevent tilting thereof. The needle walls 6 are retained in the cylinder slots which slots are undercut at their upper ends as at 9 to accommodate correspondingly shaped ends 10 of the needle walls which are beveled at 11 and provided with shoulders at 12 flush with and forming part of the recess within which the spring bands 4 are seated.

In preparing the cylinder to receive the walls 6, the outer surface of the said cylinder is cut away circumferentially transversely of the needle slots and also is undercut as at 9. The subsequent cutting of the cylinder slots leaves shoulders 5" at the upper ends of the resultant cylinder walls 5', and the heels of the needles (not shown) when in raised position would be pressed within the circumferential recess or slot by the spring bands 4, and the needle butts broken off when engaged by the needle retracting cam, unless otherwise prevented. In order to overcome the objection, the circumferential recess or slot is cut deeper than are the subsequently cut cylinder slots, and a split ring 13, cut with slots corresponding in position to the slots cut in the cylinder, is inserted therein and retained in proper position by the needle walls 6 thereafter fitted within the slots of the cylinder. The split ring 13, when in assembled position, seats within the circumferential recess or slot with the slots and walls 14 in alignment with the slots and walls 5' of the cylinder proper, and with the outer surface of the ring flush or substantially flush with the outer surface of the needle cylinder. The walls 5' and 14 are of the same shape in cross section, either to provide slots therebetween widening out somewhat as shown in Fig. 2 or slots bounded by parallel sided walls.

The split ring 13 is, preferably, formed by cutting slots in a solid ring and then split-

ting the ring into two or more sections as indicated in Fig. 4. The ring is, preferably, though not necessarily, split by cutting entirely through the ring at diametrically opposite points. When assembled within the recess of the cylinder the adjacent ends of the two half rings are separated by the width of a slot and needle walls 6 are subsequently inserted within the spaces separating the two half rings as well as within the slots of the ring sections.

The cylinder is recessed adjacent to its lower end at 15 and within the recess is seated a sectional ring 16 retained therein by means of screws 17. The two ends of the needle walls are identically shaped and when inserted within the slots of the cylinder their bevels 18, as shown in Fig. 1, project a short distance beyond or below the beveled ends 19 of the cylinder walls 5'. The lower beveled faces 20 of the sectional ring 16 rest against a correspondingly beveled face 21 forming the upper surface of a flange 22 which latter constitutes the lower extremity 25 of the cylinder. Adjacent the bevels 18 the needle walls have shoulders 23 spacing the horizontally disposed edges 24 of the needle walls from the upper faces 25 of the sectional ring 16. When the needle walls are assembled within the cylinder slots the outer faces of the walls and ring are flush. A broken needle wall may be removed and replaced by a new one by detaching a ring section.

In Fig. 1a is shown a modified form of retaining means for the needle walls consisting of a needle cylinder 26 set in a recessed ring gear 27 connected thereto as by means of screws 28. In place of the sectional ring 16 a one piece ring 29 surrounds the cylinder 40 and seats within a recess of the ring gear as shown. The upper faces of the ring 29 and adjacent edges of the needle walls 6 are shaped as are the corresponding parts in Fig. 1. The ring gear is surmounted by the usual plate 27'. In this form of the invention a broken needle wall may be removed and replaced by a new one by disconnecting the needle cylinder 26 from the ring gear 27 and then elevating the cylinder to separate the needle walls 6 from the ring 29.

In Fig. 5 is disclosed a modified form of needle walls 30. The walls have sufficient taper to converge slightly, the adjacent faces 31 thereof thus constricting the needle slots 32 at their outer or open ends.

In Fig. 6 an additional modification is disclosed, wherein the needle walls 33 are beveled on one face 34 only, and the angles at 35 are right angles.

In Fig. 7 still another modification is disclosed. The cylinder 36 has cut therein parallel sided slots and the needle walls 37 have parallel sides 38 where they are received within the cylinder slots, but diverge beyond the cylinder so that the slots 39 therebetween

are parallel sided or converge to a slight extent in a direction away from the cylinder.

In assembling the needle walls in the cylinder slots, previously cut in the outer surface of the cylinder, preferably, three sizes of walls are used, one size dimensioned to fit the slots, a second size slightly overdimensioned, and a third size of wall slightly underdimensioned. Walls of the proper dimensions are first inserted within the slots until a slot is reached within which the proper sized walls do not fit. If the proper sized wall fits loosely in the said slot, then an overdimensioned wall is inserted but, on the other hand if the proper dimensioned wall is not received within the slot of the cylinder, an underdimensioned wall is inserted. In this manner the cylinder is built up by employing three dimensions of needle walls though, as is evident, two sizes of the needle walls only

85

may be sufficient.

While as herein disclosed the present invention is concerned principally with hosiery knitting machines of the circular type adapted to reciprocate during the knitting of heels and toes, the invention is not necessarily limited to circular or hosiery machines. When applied to hosiery knitting machines of the circular type the split ring 13 functions advantageously and especially so during heel and toe or other reciprocating knitting, at which times the instep or other needles are in raised inactive position and opposite the said split ring 13.

We claim:

1. A slotted needle bed, needle walls therein, the needle bed at one end thereof being undercut to provide a recess and the walls each being reduced at one end and the said ends seated in the recess, the needle bed adjacent to the recess being grooved in a direction transverse to the slots, slotted ring sections seated within the mentioned groove, the slots therein being in alignment with and supplementing the slots in the needle bed.

2. A recessed needle bed, needle walls inserted therein, the said walls at one end being seated within the recess of the bed, a groove extending transversely of the needle walls and being formed in the outer surface of the needle bed, a slotted member being seated within the groove and supplementing the needle bed as a support for the needle walls.

3. A needle cylinder, parallel slots therein extending lengthwise thereof to provide walls therebetween, the cylinder adjacent to one end thereof being recessed and a member being seated in the said recess which member is provided with slots and walls therebetween, the said slots and walls supplementing the slots and walls of the cylinder and being in alignment therewith, in combination with needle walls which are

seated in the aligned slots of the cylinder and member.

4. In a needle cylinder of the circular type adapted to reciprocate for heel and toe knitting, slots adjacent to the upper end thereof to guide needles therein, removable needle walls below the slotted portion of the cylinder and defining therebetween slots in alignment with the slots first mentioned, the cylinder being circumferentially recessed in the outer surface thereof and between the slotted portion thereof and the upper ends of the needle walls, a slotted ring being seated within the said recess, the slots of which receive therein the removable needle walls.

5. A needle cylinder provided with slots, a portion of the slots consisting of a slotted, sectional ring, the sections of the ring being spaced from each other, removable needle walls in the slots of the cylinder and sectional ring, the spaces between the ring sections constituting slots for the reception of some of said needle walls.

6. A slotted needle cylinder, walls between the slots which walls and slots adjacent to one end of the cylinder are removed thereby to provide a groove, a supplemental member seated in the groove and which member is provided with walls and slots therebetween and in alignment with the walls and slots of the cylinder.

7. A slotted needle bed, needle walls therein, the needle bed at one end thereof being undercut to provide a recess and the walls each being seated in the recess, the needle bed adjacent to the recess being grooved in a direction transverse to the slots, slotted ring sections seated within the mentioned groove, the slots therein being in alignment with and supplementing the slots in the needle bed.

8. A recessed needle bed, needle walls inserted therein, the said walls being seated within the recess of the bed, a groove extending transversely of the needle walls and being formed in the outer surface of the needle bed, a slotted member being seated within the groove and supplementing the needle bed as a support for the needle walls.

9. A needle cylinder having slots, needle walls removably mounted in the cylinder slots and defining needle slots, an annular recess being provided in the outer face of the needle cylinder adjacent to one end of the cylinder slots and for retaining an end of each removable needle wall within its cylinder slot, an annular member seated within a portion of the annular recess and adapted to provide a lateral support for the needles.

10. A needle bed having slots therein to guide needles, walls defining said slots and being removably mounted in the needle bed, the needle bed being recessed in its outer face and adjacent to one end of the needle slots, one end of each needle wall being seated within the aforesaid recess, and a slotted

member seated within a portion of the recess in the cylinder and adapted laterally to support needles.

11. A slotted needle bed, said needle bed being recessed transversely of the aforesaid slots, a member seated in the said transversely disposed recess, the outer surface of such member being substantially flush with the outer surface of the needle cylinder.

In testimony whereof we affix our signatures.

ROBERT H. LAWSON.
AUGUSTIN GAGNÉ.
